UNITED STATES PATENT OFFICE.

ALMON E. NORRIS, OF CAMBRIDGE, MASSACHUSETTS.

HOISTING APPARATUS.

991,077.

Specification of Letters Patent.

Patented May 2, 1911.

Application filed January 14, 1905. Serial No. 241,072.

To all whom it may concern:

Be it known that I, ALMON E. NORRIS, of Cambridge, in the county of Middlesex and Commonwealth of Massachusetts, have invented an Improvement in Hoisting Apparatus, of which the following description, in connection with the accompanying drawings, is a specification, like letters on the drawings representing like parts.

13 My invention consists in improvements in hoisting and conveying apparatus and particularly in improvements relating to hoisting and conveying systems employing a cable or other track-way along which there is 15 adapted to travel a trolley carriage carrying suitable load-hoisting devices.

My invention relates particularly to the construction of, and the driving mechanism for, the winding drums which operate the 20 ropes or cables controlling the hoisting of the load, or the traversing of the carriage, or both the hoisting and the traversing; it also consists in improvements in rope guiding and equalizing devices, and in the construction of the trolley carriage itself.

My invention will be best understood by reference to the following description, when taken in connection with the accompanying drawings, of one specific embodiment there- 30 of, while its scope will be more particularly pointed out in the appended claims.

In the drawings, Figure 1 is a plan in outline of a hoisting engine provided with winding drums illustrating one form or embodiment of my invention; Fig. 2 is a side elevation of the same; Fig. 3 is an enlarged view, partially broken away and partially in section, of the winding drums and driving connections shown in Fig. 1; Figs. 4 and 40 5 are diagrammatic views showing the cable connections which may be employed, and the cable movements during hoisting and traversing respectively; and Figs. 6 and 7 show modified constructions of the winding 45 drums.

In the drawings I have shown, for illustrative purposes, a hoisting engine mounted upon the bed plate *a* provided with the two cylinders *b* and *b'*, having piston rods (one 50 of which *c* is shown in Fig. 2), connecting rods *d* and *d'* and crank disks *e* and *e'*, the latter connected directly to the drum shaft *f* (see Fig. 3). While this double cylinder, steam hoisting engine is selected to illustrate my invention, it is to be understood that the latter is not limited to any particu-

lar type or form of motive means. The drum shaft is suitably journaled in bearings *e* carried by the engine frame *a* and has upon it the two winding drums *g* and *h*, 60 which may be of any suitable construction, but which herein I have shown each of a shape adapted to be embraced by several convolutions of an endless cable to provide the necessary friction for transmitting 65 power to the trolley carriage through the cable as one strand thereof winds upon the drum and the other unwinds. The winding drums shown herein are intended to be operated at will in one direction at one speed, 70 and at a reduced speed in a reversed relation, and the means for attaining this end will be best understood by reference to Fig. 3. The drum shaft *f* has fixedly secured to it, to rotate therewith, the pinion *g'*, the 75 teeth of which mesh with one or more pinions *g*², the latter journaled upon studs *g*³ secured to and carried by the part *g*⁴, to which the drum *g* is rigidly attached. Meshing also with the pinion *g*² is an inter- 80 nal gear *g*⁵ carried by or formed upon the member *g*⁶, which latter is mounted for free rotation upon the drum shaft *f*. Near the opposite end of the hoisting apparatus and upon the drum shaft is provided a second 85 pinion *h'* keyed or otherwise secured to the drum shaft and meshing with one or more intermediate pinions *h*² journaled upon the studs *h*³, the latter being, however, secured to and carried by the member *h*⁴, which, like 90 the member *g*⁶, is journaled for free rotation upon the drum shaft. The pinion *h*² also gears with the internal gear *h*⁵, which is formed upon or carried by the part *h*⁶ fix- 95 edly attached to the winding drum *h*. The free rotatable members *g*⁶ and *h*⁶ have 100 formed upon their peripheries suitable brake surfaces embraced by the brake bands *g*⁷ and *h*⁷ respectively, which are so connected to the rocker shaft *i* (Fig. 1) that a movement of the hand lever *i'* (Fig. 2) connected to the rocker shaft *i* through links *i*² and *i*³, will serve to securely and simultaneously clasp the said bands *g*⁷ and *h*⁷ 105 about the surfaces of their respective brake drums to oppose and completely stop further movement thereof. When this takes place, rotation of the drum shaft drives the pinion *h'* in one direction, the pinion *h*², the axis of which is now stationary, in the 110 opposite direction, and the gear *h*⁵ and the drum *h* also in an opposite direction and at

a suitably reduced speed. The pinion g' rotating in the same direction as the pinion h' causes the pinion g^2 to move and travel about the internal gear g^3 , now held fast, so 5 that the drum g is caused to rotate in the same direction as the pinion g' and oppositely to the drum h . The relative sizes of the different gears is preferably such that while the two drums g and h rotate in opposite 10 site directions, as has been seen, and at a speed relatively less than that of the shaft f , the speed of the two winding drums is substantially the same.

Referring now to Figs. 4 and 5, I have 15 there indicated diagrammatically the relation of the operating cables to the winding drums g and h and the trolley carriage. The latter designated by k , is adapted to run upon the cable-way l . In the simplest 20 and preferred embodiment of my invention the carriage is provided with two winding drums k' secured each to one end of the depending hoisting rope k^2 carrying the skip hook k^3 and adapted when oppositely rotated to raise or lower the said hook. Secured to the hoisting drums k' are the larger 25 winches k^4 , about which are carried with several turns the opposing loops l' and l^2 of the operating cable system which herein, 30 and preferably, comprises a single endless cable. The strand l^3 of the loop l' passes to the end of the cable-way at which the drums g and h are located, to and about the drum h and returning forms the strand l^4 , 35 which passes to the opposite end of the cable-way and thence about suitable sheaves again to the trolley carriage to form one strand of the loop l^2 . The other strand l^5 of the loop l' passes to and about the drum g 40 and thence forming the strand l^6 passes to the opposite end of the cable-way and thence to the carriage to form the remaining strand of the loop l^2 .

When the brake bands g^7 and h^7 are 45 tightened to throw in the slow reverse speed, the drums g and h rotate in the relations shown in Fig. 4 and cause the respective strands of the endless cable to move in the directions indicated by the arrows, from 50 which it will be seen that the winches k^4 are caused to be oppositely rotated to raise the hook k^3 and effect hoisting of the load. During this operation no change in position of the carriage is effected, for the loops l' 55 and l^2 remain of the same length, one strand of each being paid out as rapidly as the other is drawn in.

When the load has been hoisted and it is desired to cause travel of the carriage, the 60 latter may be effected by producing conditions of cable movement shown in Fig. 5, where it will be observed that the direction of movement of the drum h has been reversed, the new relative rotation of the 65 drums preferably taking place, as it will

appear, at an increased speed. As will be seen from the arrows indicating the direction of cable movement, this causes a similar movement of each strand of the two opposing loops, so that one loop is lengthened 70 while the other is correspondingly shortened with the result that, without movement of the winches k^4 or hoisting drums k' , the carriage has traversed in the direction of the shortened loop. Thus, in 75 Fig. 5, the loop l' will continue to be lengthened and the loop l^2 shortened so long as the rotation of the drums g and h is carried on and the trolley carriage k will be moved to the left, the hook and its attached 80 lead however being held in its initial elevated position.

Referring now to Fig. 3 and also to Figs. 1 and 2, the reverse movement of the winding drums is preferably effected by causing 85 them to be driven directly from the driving shaft f . In the form of my invention shown in Fig. 3, a clutch member m is fixedly secured to the shaft l intermediate the rotatable members g^6 and h^6 . The latter are provided with cone-shaped surfaces g^8 and h^8 , respectively, which overlie and co-operate with corresponding surfaces upon the clutch member m , in connection with suitable friction material m' intermediate 90 the two sets of surfaces, forming thereby a clutch device for clutching the rotatable members to the shaft. The two clutches are thrown simultaneously into engagement 95 through any clutch-operating device, such as that illustrated in re-issued Letters Patent No. 12,085 granted to me February 24, 1903. For this purpose there is provided a collar n slidably mounted on the shaft f and adapted to be forced against 100 the abutting face of the drum-carrying element g^6 by the clutch-operating screws n' threaded in a stationary abutment formed by a part of the engine frame. The clutch-operating screws are moved to slide the collar along the shaft by means of levers n^2 110 (Figs. 1 and 2) connected by suitable linkage to the rocker shaft n^3 , the latter in turn being connected through links n^4 to the clutch-operating lever n^5 and under control 115 of and near the operator. A second sliding collar (broken away in Fig. 3) is also located at the opposite end of the shaft abutting against the face of the drum-carrying element h^6 and is adapted to be forced 120 against the latter by means of clutch-operating screws and levers, the latter also connected to the rocker shaft n^3 in the same manner as has been already described. Movement of the clutch-operating lever 125 causes simultaneous inward movement of the two sliding collars and also of the two slidably mounted drum-carrying members, the latter having their inward peripheral faces in abutment against the faces of the rota- 130

table members g^6 and h^4 , which are also 5
slidable on the shaft, so that the members
 g^6 and h^4 are caused to be moved inwardly
and with their cone surfaces in frictional
engagement with the surfaces of the clutch
member f . When this takes place in each
10 case two of the three gearing elements are
fixed relatively to the shaft and the third
element carried by each winding drum is
also locked directly to the driving shaft.

The full operation of the device will be
apparent. The carriage is traversed from
one point to another at the relatively high
rate of speed by throwing the clutch-operat- 15
ing lever to drive the winding drums shown
in Fig. 5 directly from the driving shaft.
When properly positioned the carriage may
be held with or without its load by holding
the driving shaft against rotation, which
20 may be done through the engine itself or by
the brake bands g^7 and h^5 , if desired. When
the load is ready for hoisting, the clutch
lever may be thrown out of engagement and
the friction lever into engagement to give
25 the relatively slow reverse movement to the
drums. When suitably elevated, the load
is again traversed by throwing the clutch
into and the friction out of engagement.

The reversal of the hoisting or traversing
30 movement may be effected by permitting re-
verse movement of the driving motor. In
the present instance I have provided a suit-
able reversing gear indicated in outline in
Fig. 2 (but partly removed from Fig. 1)
35 and operated from the rock shaft o , the
latter in turn being moved through links o'
and the reversing lever o^2 .

The slow speed which is utilized on the
40 hoisting movement permits the application
of increased power to the lifting of the load
without, however, bringing any material
strain upon the brake bands, since but a
fractional part of the entire load is required
45 to be held by each band. The members g^6
and h^4 which constitute the rotatable mem-
bers of each planetary gearing system, are
preferably provided with means which
maintain them in generally the same rela-
50 tive position, such means herein being a
series of pins m^2 which are secured to a
radial flange m^3 upon the member h^4 and
pass loosely through oppositely located holes
in a corresponding flange upon the member
55 g^6 . This permits each clutch face to adjust
itself to its corresponding friction surface
when the clutch is thrown into engagement,
while still maintaining the two clutch mem-
bers in a generally fixed relation. By secur-
60 ing the movable members together, the
actual force necessary to apply to the clutch
for holding the load while the carriage is
being traversed, is reduced, for the plane-
tary gearing connection between the shaft
65 and the two members g^6 and h^4 being re-
versed the strains upon the two clutch faces

are in opposite directions permitting the
greater to be partly neutralized by the lesser.

Many variations in the relation of the
driving elements will be evident to those
skilled in the art and I have deemed it un- 70
necessary to refer to any save those shown
in Figs. 6 and 7, it being understood that my
invention is in no respect limited in the de-
tails or relative arrangement of parts in
any of the specific illustrations shown. 75

In Fig. 6 I have shown the driving pin-
ions and drums mounted upon the driving
shaft f in substantially the same relation as
shown in Fig. 3, but the stationary clutch
member m is here dispensed with and the 80
rotatable members, namely, the pinion h^2
and the internal gear g^5 of the two systems
of planetary gearing, are carried upon one
and the same rotatable element p , and the
latter is directly clutched to the drum-carry- 85
ing members h^6 and g^4 to cause interlocking
of the planetary gearing in each case for the
direct drive of the drums from the driving
shaft. This construction recommends itself
for its simplicity, but since the two drums 90
lack the common clutching effect of the con-
struction shown in Fig. 3, and are separately
clutched to the rotatable member p , the
effect of the two clutches is accumulative
and a greater force is required to effect the 95
clutching in the hoisting apparatus of Fig.
6 than in that of Fig. 3, and I accordingly
prefer the latter in practice.

In Fig. 7 I have shown the two drums
with their driving mechanism upon separate
shafts f and f' . In this case the rotatable
members h^4 and g^6 are connected through
intermeshing gear teeth q , thus preserving
a fixed relation at all times between the re- 100
spective planetary gearing elements carried
by and rotating therewith. Separate clutch
members m^5 and m^6 are fixedly secured upon
the two shafts and are also connected by
intermeshing gear teeth r , one with the
other. Each clutch member is adapted to 105
be engaged with its adjacent and correspond-
ing rotatable member through friction
clutches m^7 and m^8 by means of suitable
clutch-operating devices (not shown). Since
the clutch members m^5 and m^6 are geared 110
together, obviously a single clutch m^7 or m^8
could be used if desired. The single brake
band m^9 encircling the member g^6 is suffi-
cient to hold stationary both rotatable mem- 115
bers when a slow speed hoisting movement is
desired.

It is to be understood that my invention is
not limited to the various details or form
and arrangement of parts which have been
herein described, the same being submitted
for illustrative purposes, but that many 125
modifications may be made in the system,
as I have herein described the same, with-
out departing from the spirit of my inven-
tion.

I claim.

1. In an apparatus of the class described the combination with a driving shaft, a pair of winding drums coaxially arranged thereon, means for positively rotating said drums from said shaft at one speed in the same direction or at a different speed in opposite directions.

2. In an apparatus of the class described, 10 the combination with a driving shaft of a pair of winding drums coaxially arranged thereon, means for driving both of the drums from said shaft directly at one speed in the same direction, and planetary gearing 15 between the said shaft and each of said drums for driving the same at a different speed in opposite directions.

3. In an apparatus of the class described, 20 the combination with a driving member, of a pair of winding drums, speed reduction gearing between the driving member and the winding drums to drive the latter and clutch means common to said drums and between the latter and said driving member to drive 25 the drums at another speed.

4. The combination with a pair of winding drums, of driving means therefor, means for driving said drums from said driving means at one speed, and planetary gearing 30 for driving said drums at a reduced speed, said gearing comprising in each case a rotatable gearing member, the rotatable gearing member for one drum being connected to the rotatable gearing member for the other.

5. The combination with a pair of winding drums of driving means therefor, planetary gearing driving said drums at a reduced speed, said gearing comprising in each 40 case a gearing member carried by the drum, a gearing member connected to the driving means and connected rotatable members and means for clutching the rotatable members to the driving means for driving said drums directly from said driving means.

6. The combination with a pair of winding drums of driving means therefor, and additional driving means comprising planetary gearing for driving the same at a reduced speed, said gearing comprising in each 50 case a rotatable gearing member, means for opposing movement of said rotatable gearing members, and means for clutching the same directly to the driving means.

7. The combination with a pair of winding drums, of driving means therefor, and additional driving means comprising planetary gearing for driving said drums at a reduced speed, said gearing comprising in each case a rotatable gearing member, means 60 for opposing movement of said rotatable gearing member to render effective said planetary gearing, and means for interlocking said planetary gearing to cause direct drive from said driving means to said drums.

8. The combination with a pair of winding drums of driving means therefor, and additional driving means comprising planetary gearing for driving said drums at a reduced speed comprising in each case a gearing element connected to the drum, and a gearing element connected to the driving means and a gearing element connected to a rotatable member, means for opposing movement of the rotatable members to render effective said planetary gearing, and means for interlocking said gearing for direct drive from said driving means to said drum. 70

9. The combination with a pair of winding drums of driving means therefor, and additional driving means comprising planetary gearing for driving said drums at a reduced speed comprising in each case a gearing element connected to a drum, a gearing element connected to the driving means and a gearing element connected to a rotatable member, means for opposing movement of said rotatable members, and means for clutching said members directly to the driving means. 80

10. The combination with a driving shaft of a pair of winding drums upon said shaft, planetary gearing for driving said drums in opposite directions at a reduced speed comprising in each case a gearing element 90 connected to a drum, a gearing element connected to driving means, and a gearing element connected to a rotatable member, means for opposing movement of said rotatable members, a member intermediate the same secured to said shaft, and means for clutching said rotatable members to said intermediate member. 95

11. In an apparatus of the class described, a rope-winding device having a pair of 105 rope-winding drums, a driving shaft, means for connecting said drums to said shaft for similar driving movement, and planetary gearing means for driving the same in relatively reverse directions at a different speed 110 for a different rope-winding movement.

12. A rope-winding device having a driving shaft, a pair of drums adapted to be connected to said shaft for similar driving movement, and planetary gearing for at 115 least one of said drums whereby the latter may be driven in a reverse direction at a reduced speed.

13. A rope-winding device having a driving shaft, a pair of drums adapted to be 120 connected to said shaft for similar driving movement, and planetary gearing between the drums and said shaft whereby the former may be driven in opposite directions at a reduced speed. 125

14. In an apparatus of the class described, a plurality of winding drums co-axially arranged, a driving shaft therefor, and planetary gearing between said shaft and each of said drums. 130

15. The combination with a winding drum, of a driving shaft therefor, a clutching device on said driving shaft, planetary gearing between the drum and shaft comprising a gearing member connected to the shaft, a gearing member connected to the drum and a rotatable gearing member for clutching said rotatable member to the clutching device or for holding the same stationary.

16. The combination with a pair of winding drums, of a driving shaft on which the same are co-axially arranged, a clutching member between said drums, planetary gearing between said shaft and each of said drums comprising in each case a gearing member driven by the shaft, a gearing member secured to the drum and a rotatable gearing member and means for clutching the rotatable member, in each case, to the clutching member or for holding the same fixed.

17. The combination with a pair of winding drums, of a driving shaft on which the same are co-axially arranged, a clutching member between said drums, planetary gearing between each shaft and each of said

drums, comprising, in each case, a gearing member driven by the shaft, a gearing member secured to the drum and a rotatable gearing member, and means for clamping the rotatable member, in each case, to the clutching member for holding the same fixed, the two rotatable members being connected to rotate together.

18. The combination with a pair of winding drums, of planetary gearing for driving each of said drums, comprising, in each case, a driven gearing member, a gearing member secured to the drum, and a rotatable gearing member, said rotatable gearing members being connected to be turned one with the other, clutching means, means for clutching the rotatable members to the clutching means, and means for holding the rotatable members fixed.

In testimony whereof, I have signed my name to this specification, in the presence of two subscribing witnesses.

ALMON E. NORRIS.
